UNITED STATES PATENT OFFICE.

ANTOINE P. PLAUT, OF FLINT, MICHIGAN, ASSIGNOR OF ONE-HALF TO THE ROBERTS
BRASS MANUFACTURING COMPANY, OF DETROIT, MICHIGAN, A CORPORATION OF
MICHIGAN.

CARBURETOR.

Application filed January 3, 1918, Serial No. 210,144. Renewed February 27, 1925.

To all whom it may concern:

Be it known that I, ANTOINE P. PLAUT, a citizen of the Republic of France, residing at Flint, in the county of Genesee and State of Michigan, have invented certain new and useful Improvements in Carburetors, of which the following is a specification, reference being had therein to the accompanying drawing.

10 This invention relates to certain new and useful improvements in carburetors, the object being to provide a carburetor without any movable parts whereby a richer mixture for the slower speed and idling of the 15 engine to which the carburetor is attached, can be obtained automatically in a positive and a controllable manner, the specific construction being such that by using the laws of flow of fluids in pipes any desired size 20 of carburetor can be made according to calculations.

Another object of my invention is to provide a carburetor with a main emulsifying chamber and an auxiliary expansion chamber, the auxiliary accelerating chamber being provided with a fuel inlet and having a series of air inlets whereby the fuel entering said chamber is partly atomized before it enters the main emulsifying chamber.

30 Another and further object of the invention is to provide a carburetor which is extremely simple and cheap in construction and one in which the parts are so arranged and connected together that they can be readily assembled or taken apart.

Another and further object of the invention is to provide a carburetor with novel means for delivering fuel to the motor when idling or running the motor without a load.

40 Other and further objects and advantages of the invention will be hereinafter set forth and the novel features thereof defined by the appended claims.

With these objects in view,

45 Figure 1 is a vertical section through my improved construction of carburetor.

Figure 2 is a section taken on line 2—2 of Fig. 3, showing the air chamber and the auxiliary expansion chamber.

50 Figure 3 is a horizontal section showing the position of the expansion chambers and air chambers; and

Figure 4 is a top plan view of the same. Like numerals of reference refer to like

parts in the several figures of the drawing. In carrying out my invention I employ a body 1 which is preferably formed of a casting having an air passage 2 provided with a lateral inlet 3 in which is mounted a valve 4 for controlling the admission of air, said valve being carried by a stem 5 having an arm 6 connected thereto to which is adapted to be connected a dash control device in order to allow the position of the valve 4 within the air inlet to be adjusted for the purpose hereinafter fully described. The air passage 2 is provided with a threaded upper end 7 into which is adapted to be screwed the threaded portion 8 of a Venturi tube 9 which terminates at its upper end in a throttle chamber 10 in which is mounted a throttle valve 11 of the ordinary construction. The wall of the throttle chamber is provided with the usual flange for connecting the same to the intake manifold of the engine.

The Venturi tube extends down into the air passage as clearly shown, and is provided with an exterior annular groove forming a main annular emulsifying chamber 12 from which extends a series of diagonally arranged passages 13 which communicate with the interior of the Venturi tube at the most restricted portion thereof so as to form a plurality of jets through which the partially atomized fuel is delivered into the Venturi tube.

The annular emulsifying chamber 12 communicates with an auxiliary accelerating chamber 14 formed in the body 1 through a bore or passage 15 and the auxiliary accelerating chamber is formed with a threaded lower end into which is screwed a fuel nozzle 16 in order to allow the same to be adjusted within the auxiliary accelerating chamber for the purpose hereinafter fully described. The fuel nozzle 16 is provided with a calibrated opening which communicates with a hollow nipple 17 formed on the body, said nipple having a drain cock 18 screwed therein for closing the lower end thereof and to provide means for draining the fuel from the fuel reservoir.

The auxiliary accelerating chamber 14 is provided with a series of air inlet ducts 19 extending from an air chamber 20 formed in the body parallel with the auxiliary accelerating chamber. The air chamber 20 is

provided with an air tube 21 at its upper end in which is screwed a tubular valve 22 the lower end of the valve being adapted to seat on a valve seat 23 formed in the air tube. The walls of the air tube are provided with openings 21' for admitting additional air when desired, and it will be seen by this construction that by having the tubular valve with the calibrated air passage 10 a predetermined quantity of air will be admitted to the air chamber at all times, and by the particular construction of valve and air inlets an additional supply of air can be admitted into the air chamber by opening 15 the valve.

The body 1 has formed integral therewith a fuel reservoir 24 which is provided with a fuel outlet 25 extending downwardly into the nipple 17 so that fuel from the reservoir 20 will pass through the nozzle 16 and be delivered into the auxiliary accelerating chamber 14. The fuel reservoir 24 is closed by a removable cover 26 which is provided with a fuel inlet nipple 27 to which the supply pipe is adapted to be connected. The cover is provided with a valve seat 28 to receive a valve 29 controlled by a float 30 mounted in the fuel reservoir for maintaining fuel within the reservoir at a level, 30 approximately, on the line A—A which is midway of the annular main emulsifying chamber.

One wall of the Venturi tube 9 is enlarged as shown at 31 and is provided with a vertical bore 32 in which is arranged a tube 33, the lower end of which extends into the annular emulsifying chamber slightly below the fuel level, and the upper end communicates with a diagonally upwardly extending bore 33' which extends into the throttle chamber above the throttle valve thereof. The bore 33' is provided with a valve seat 34, back of the bore 32 and in which is adapted to be seated a needle valve 35 for controlling the admission of auxiliary air through an air inlet 36 as clearly shown.

When the carburetor is in position on an engine, fuel will accumulate in the main and auxiliary accelerating chambers 12 and 14, respectively, and the air chamber 20, until it reaches the level, approximately, midway the height of the main emulsifying chamber and when the motor is started this accumulated fuel will be forced out of the jets 13 by the current of air passing through the air ducts which produces a drop in pressure in the throat of the Venturi tube, by the velocity of the air going therethrough. This drop in pressure is felt in the main and auxiliary accelerating chambers according to the quantity of air admitted through the air ducts from the air chambers, that is, if the area of the air ducts is half the area of the jets 13, the drop in pressure in the expansion chamber 12 will be only half of what it will be in the throat of the Venturi tube. The adjustable nozzle arranged in the bottom of the auxiliary accelerating chamber will therefore be subjected to this last depression, and as the nozzle has its 70 opening below the fuel level in the fuel reservoir it will give a certain quantity of fuel, according to the suction plus another certain quantity, according to the difference in level, this being regulated by adjusting 75 the position of the nozzle into or out of the auxiliary accelerating chamber.

When the engine is idling or the motor is running without a load the velocity of the air through the Venturi tube is then too low 80 to draw the fuel through the jets 13, and the fuel will be picked up from the main emulsifying chamber by the tube 32 and discharged above the throttle, and in this way no more fuel can be fed into the motor than 85 can be discharged into the main emulsifying chamber, and as the passage is of such a size as to take care of many times as much fuel as will find its way into the main emulsifying chamber the air as well as the fuel 90 will be drawn therethrough, which on account of its velocity helps to carry the fuel and break it up before it is delivered above the throttle. The suction can be regulated 95 by the needle controlling the air inlet from the atmosphere.

In the operation of the carburetor, constructed in accordance with my invention, when the engine is being started the valve 4 in the air inlet is preferably closed, and as fuel from the fuel reservoir has accumulated within the main and auxiliary chambers and the air chamber which is always open to the atmosphere, a partial vacuum is created within the Venturi tube so as to cause 100 the fuel to be drawn out of the main expansion chamber through the multiplicity of jets, and as the fuel level is gradually reduced in these chambers the jets of air from the air chamber gradually pick up and 105 atomize the fuel in the auxiliary accelerating chamber until the accumulated supply 110 has been exhausted so that the initial mixture is very rich so as to facilitate the starting of the motor to which the carburetor is 115 attached. As the motor continues to run, fuel is constantly being delivered into the auxiliary expansion chamber through the nozzle, and as air is entering this chamber 120 through the series of air jets the fuel is partially atomized, and by the suction of the engine is drawn into the main emulsifying chamber from which it is delivered into the Venturi tube through the series of jets so 125 that the incoming air will absorb and completely mix the partially mixed explosive mixtures before it is delivered into the engine, it of course being understood that the valve in the air inlet is only held closed on 130 starting the motor.

The fuel level is maintained approximately midway of the emulsifying chamber 12 of the compound chambers and when the motor is started, whatever fuel is in the chambers 12 and 14 as well as in the chamber 19 will be rushed out through the atomizing jets 13 by the currents of air blowing through the air ducts 19 on account of the drop in pressure produced in the throat of the venturi by the velocity of the air going through, this drop in pressure being felt in chambers 12 and 14 according to the quantity of air admitted through the ducts 19, that is, if the area of the air ducts 19 is half the area of the jets 13, the drop in pressure in the chambers will be only half of what it would be in the throat of the venturi; the nozzle 16 at the bottom of the chamber 14 will therefore be subjected to the last depression, because the nozzle 16 has its opening below the fuel level in the float chamber. This nozzle delivers a certain quantity of fuel according to the suction plus another certain quantity according to the difference in level, this last quantity being regulated by letting the end of the nozzle project more or less into the chamber 14.

This construction provides means for delivering to the engine the proper mixture according to its load, and when the engine is idling the throttle is substantially closed, and the velocity of air passing through the Venturi tube is reduced to such an extent as to be too low to carry the fuel, and as the passage connected with the throttle chamber above the throttle is in communication with the main emulsifying chamber, fuel and air will be drawn from the emulsifying chamber and delivered above the throttle from which it will be sucked to the engine so as to deliver the proper mixture thereto.

I claim:

1. A carburetor comprising a body having an air passage being provided with a constant level fuel reservoir, a Venturi tube

mounted in the upper end of said air passage, an exterior annular groove formed on said Venturi tube forming an annular chamber, said annular chamber being in communication with said Venturi tube through a series of unclosable passageways, an auxiliary chamber in communication with the annular chamber, a nozzle disposed in said auxiliary chamber below the fuel level of said reservoir and an air reservoir having a plurality of ducts communicating with said auxiliary chamber.

2. A carburetor comprising a body having an air passage provided with a valve control air inlet, a Venturi tube mounted within the upper end of said air passage having a throttle valve at its upper end, a constant level fuel reservoir, a chamber surrounding said Venturi tube and in communication therewith through a series of unclosable passageways, an auxiliary chamber in communication with the annular chamber, a fuel nozzle extending into said auxiliary chamber for delivering fuel constantly thereto, and an air chamber having a series of ducts disposed in different horizontal planes communicating with said auxiliary chamber.

3. In a carburetor, the combination with a constant level fuel reservoir, of a vertically disposed Venturi tube having an annular emulsifying chamber in communication therewith through a series of unclosable passageways, the bottom of said emulsifying chamber being below the fuel level of said reservoir, an auxiliary chamber forming an accelerating well having a fuel nozzle at its bottom below the fuel level of said reservoir and in open communication with said annular emulsifying chamber, an air chamber and a series of air ducts communicating with said accelerating well.

In testimony whereof I hereunto affix my signature.

ANTOINE P. PLAUT.
